UNITED STATES PATENT OFFICE.

OWEN THOMAS DOUGHERTY, OF MINNEAPOLIS, MINNESOTA.

GAME TOY.

SPECIFICATION forming part of Letters Patent No. 536,193, dated March 26, 1895.

Application filed May 8, 1894. Serial No. 510,452. (No model.)

To all whom it may concern:

Be it known that I, OWEN THOMAS DOUGHERTY, a citizen of the United States, residing at Minneapolis, in the county of Hennepin and State of Minnesota, have invented certain new and useful Improvements in Game Toys; and I do hereby declare that the following is a full, clear, and exact description of the invention, such as will enable those skilled in the art to which it appertains to make and use the same.

My invention relates to improvements in game toys.

The object of my device is to produce a toy which will furnish amusement, while also involving the practice of some skill.

The invention will first be described in connection with the accompanying drawings and then particularly pointed out in the claims.

20 In the drawings—Figure 1 is a perspective view of a device embodying my invention, in position for operation. Fig. 2 is a longitudinal section of the same as it appears at the end of the operation.

25 Referring to the drawings, A is a standard having a bifurcated lower portion, a, this standard being preferably made as a manikin, representing the figure of a man, the lower bifurcated portion being the legs of the 30 manikin. In the forked portion, a, is fulcrumed a lever, B, having a plate, b, at one end, and a thumb-piece, b', at the other end, the lever being preferably fulcrumed by a pin passing through the two lower portions of the 35 standard and through the lever, as will be understood from the drawings. The standard is secured to a base-piece, C, preferably circular in general outline, with a projection, c, at the rear, the purpose of which will be described 40 hereinafter.

D is a missile, preferably of lead and in the shape of a hat.

In using my device, the missile may be placed on the plate, b, of the lever, B. By 45 then suddenly pressing down upon the thumb-piece, b', the missile will be thrown upward and toward the standard. The object of the game is to throw the missile on top of the

standard. In other words, if the standard be in the shape of a man, and the missile in the 50 shape of a hat, the object is to put the hat on the head of the figure, by a jerk on the lever.

The game may be modified by placing the missile on the projection, c, of the base-piece, C, and then, by a suitable movement of the 55 base-piece in the hands of the player, jerking the hat on top of the head of the figure.

One very amusing way of playing the game is to have several persons divided into two parties, each party playing as an antagonist 60 of the other party, and each player provided with a toy device of the kind just described, the object of the game being to see which party can first place all the hats on all the heads of their respective devices.

Having thus fully described my invention, what I claim as new, and desire to secure by Letters Patent, is—

1. In a game toy, the combination, with a standard, and a lever pivoted to the standard, 70 of a missile arranged to fit over the top of the standard, and capable of resting on the lever, substantially as set forth.

2. In a game toy, the combination, with a standard having a lower bifurcated portion, 75 of a lever fulcrumed in the bifurcated portion of the standard, and a missile arranged to fit over the top end of the standard, substantially as set forth.

3. In a game toy, the combination, with a 80 base-piece having a projection, a standard secured to the base piece and having a lower bifurcated portion, of a lever fulcrumed in the bifurcated portion, said lever having a plate at one end and a thumb-piece at the other 85 end, and a missile arranged to rest either on the projection of the base-piece or on the plate of the lever, and capable of fitting on top of the standard, substantially as set forth.

In testimony whereof I have hereunto set 90 my hand in presence of two subscribing witnesses.

OWEN THOMAS DOUGHERTY.
